UNITED STATES PATENT OFFICE.

FRANCIS M. LOWDEN AND JOHN D. LOWDEN, OF LAWRENCE, INDIANA.

IMPROVEMENT IN CLOD-FENDERS.

Specification forming part of Letters Patent No. 97,785, dated December 14, 1869.

To all whom it may concern:

Be it known that we, FRANCIS M. LOWDEN and JOHN D. LOWDEN, of Lawrence, in the county of Marion, and in the State of Indiana, have invented an Improved Clod-Fender; and we do hereby declare that the following is a full, clear, and exact description thereof, reference being had to the accompanying drawing, and to the letters of reference marked thereon.

The nature of the invention consists in the construction and use of the clod-fender hereinafter described, said device to be made of iron or any other convenient and suitable material.

To enable others skilled in the art to make and use our said invention, we proceed to describe more fully, as follows:

A B of the accompanying drawing is a section of the plow-beam.

E F G H I is a rod of iron, bent in the shape there represented, passing, in the form of a screw-tine, through the beam at E, and passing through a loop of metal represented by C, which is secured to the beam by a bolt-tine at D. To this rod E F G H I are attached three other smaller rods, K L, M O, and P S, in the way represented in the drawing, so that H I, K L, M O, and P S will all be parallel to each other. This is for a right-hand clod-fender; but if it be desired to make a left-hand fender, the bend at E and the bend between

G and E may be reversed, so as to stand the other way, and the fender will be suitable for the left-hand side of the plow.

To use my said invention, it is attached to the plow-beam aforesaid, and used as any other clod-fender. It will be found that by putting on one jam-nut at E and another at D that the distance of the fender from the plow can be regulated at pleasure. The fender being free to oscillate around E and vibrate in the loop C, it will be found readily to rise and pass over any obstructions that may meet it in passing through the field. By reason of the fact that the tines H I, K, L M O, and P S are parallel, and have no cross-pieces on them to form any obstruction, it will also be found that they will keep all the time clean, and not at any time get clogged up with dirt or any other truck.

What we claim, and desire to secure by Letters Patent, is—

The clod-fender herein described, when the same is constructed in its said several parts and used substantially as herein set forth.

In testimony that we claim the foregoing specification we have hereunto set our hands this 18th day of June, 1869.

FRANCIS M. LOWDEN.
JOHN D. LOWDEN.
